VEHICLE WHEEL

Maurice P. Chandler, Utica, and William L. Porter, Birmingham, Mich., assignors to General Motors Corporation, Detroit, Mich.

Filed Dec. 7, 1970, Ser. No. 26,311

Term of patent 7 years

Int. Cl. D12—16

U.S. Cl. D14—30

FIG. 1 is a front elevational view of a vehicle wheel showing our new design;

FIG. 2 is a sectional view taken generally along the plane indicated by line 2—2 of FIG. 1; and

FIG. 3 is a perspective view.

We claim:

The ornamental design for a vehicle wheel, substantially as shown.
